(57) **CLAIM**

I claim the ornamental design of a little ben timer, as shown
and described.

DESCRIPTION

FIG. 1 is an isometric view of the little ben timer;
FIG. 2 is a front view;
FIG. 3 is a back view;
FIG. 4 is a right side view, which is a mirror image of the
left side view;
FIG. 5 is a top plan view; and,
FIG. 6 is a bottom plan view.
